F. J. QUIST.
CARPET CLEANER.
APPLICATION FILED JAN. 13, 1913.

1,198,479.

Patented Sept. 19, 1916.

UNITED STATES PATENT OFFICE.

FRANK JULIUS QUIST, OF WORCESTER, MASSACHUSETTS.

CARPET-CLEANER.

1,198,479.

Specification of Letters Patent. Patented Sept. 19, 1916.

Application filed January 18, 1913. Serial No. 741,628.

To all whom it may concern:

Be it known that I, FRANK J. QUIST, a citizen of the United States, residing at Worcester, in the county of Worcester and 5 State of Massachusetts, have invented a new and useful Carpet-Cleaner, of which the following is a specification.

This invention relates to a carpet cleaner.

The principal objects thereof are to provide a simplified and practically operating combination between an ordinary pneumatic carpet cleaner and a rotary brush carpet sweeper.

It has been found in practice that the 15 brush carpet sweepers and the pneumatic carpet cleaners are to a certain degree complementary to each other, each one being capable of accomplishing certain results not accomplished in a high degree by the other.

20 I am aware of the fact that several attempts have been made to combine the two devices, but so far as I am aware they have generally involved either the placing of the rotary brush in the nozzle of the pneumatic device,

25 in which case the pneumatic device does nothing except to take up and carry away the air and dust stirred up by the brush, or they have involved complicated mechanism, costing to build at least as much as

30 the combined cost of a pneumatic and a brush cleaner. This invention is made for the purpose of combining these elements in a new way so as to avoid these objections, and to get the results of both the pneumatic cleaner and the sweeper, and also to provide 35 for the operation of either one of them independently of the other without the employment of complicated mechanism for making the change.

40 The invention also involves improvements in details of construction as will appear hereinafter.

Reference is to be had to the accompanying drawings in which—

45 Figure 1 is a side elevation of a pneumatic carpet cleaner of a type such as that represented in the patent to myself and Malcolm Blanch, reissued on the 7th day of January, 1913, No. 13,508 with a rotary sweeping attachment thereon in accordance with this invention; Fig. 2 is a fragmentary end view of the same; Fig. 3 is a plan of a portion thereof; and Fig. 4 is a longitudinal sectional view through one end on the line 50 4—4 of Fig. 3.

It will be seen that I have shown the in-

vention as applied to a pneumatic carpet cleaner comprising a casing 10, wheels or roller supports 11 near one end for supporting that end of the casing, said wheels being mounted on a shaft 12 and having cranks 13 for operating arms or pitmen 14 which are connected with the suction creating devices or bellows 15. These bellows take air from a chamber 16 in which is located a dust bag 17 or the like, provided with a nozzle 18 at the outer end secured in this instance by screws and thumb nuts 19. A roller 20 is provided having an adjusting screw 21 for two purposes, first, to adjust the nozzle into proper relation with the surface over which it is traveling, and second, to raise it entirely out of contact with that surface when desired in order to render this part of the apparatus inoperative. It will be seen that 75 the wheels, as has been the case with this class of instruments before, are located in depressions or socket 25 in the sides of the casing, so that they do not project from it, and that they are provided with rubber tires 80 or rims. Therefore, as they pass over the floor they are turned by the motion of the casing along the floor or carpet so as to operate the bellows.

As so far described, the instrument is one 85 which can be used as a pneumatic cleaner without further attachments and it is a complete pneumatic cleaner in itself. For the purpose of adding the positive sweeping feature, a very simple arrangement is provided. The end of the casing beyond the 90 wheels is discontinued below the surface 26 and on the end of the casing is fixed an auxiliary casing 27 of small size. This is shown as having an upwardly extending 95 flange 28 provided with elongated openings 29 through which fastening screws or bolts 30 are passed, so that this casing can be arranged in any desired adjusted position. The top of the auxiliary casing extends 100 downwardly at a slant and it also has a projecting part 31 extending back under the bearings of the shaft 12. Mounted on the outside of this casing are a pair of pivoted brackets 32 provided with adjustable bearings 33 for the ends of a brush shaft 34. This shaft has a cylindrical brush 35 thereon, and it is also provided with a pair of wheels or rollers 36 outside the auxiliary casing, in this instance. On the 105 top of the auxiliary casing in the center of the nozzle is a spring 37 having two de-

pressions 38 and 39, and connected with the two brackets is an operating rod 40 of bail form adapted to be swung forward and back into either of these depressions. When in 5 the inner depression 39 the brackets are swung back toward the wheels 11, so that the wheels 36 come into contact with them, and the rotation of the driving and supporting wheels 11 results in rotating the wheels 10 36 and consequently the brush. When the rod 40 is brought forward into the depression 38 the brackets, brush, and shaft are elevated so as to bring the brush out of contact with the floor, and at the same time 15 the wheels 36 out of contact with the tires on the wheels 11. This renders the brush inoperative both because it stops rotating and because it is out of contact with the floor.

20 It will be remembered that the pneumatic cleaner is provided with a dust collecting device 17 near the nozzle, and in a similar way the brush cleaner is provided with dust collecting devices on each side thereof. One 25 of these is shown as a pivoted pan 45 located just at the end of the auxiliary casing, and having an operating arm 46 for swinging it down against the action of a spring 47 to permit of its being emptied. The other one 30 is also in the form of a pan 48 pivoted on the projections 31 and provided with springs 49 for holding it in horizontal position. It is provided also with an extending lip 50 which projects beyond the shaft 35 12 and engages the bottom of the main casing 10, being provided with an operating arm 51 or other device for forcing it open. In this way it will be seen that this pan not only catches the dust from that side of the 40 brush but also catches any dust that can collect inside of that end of the casing of the pneumatic cleaner and fall down through the space above the shaft 12.

The operation of the device is very simple. When the rod 40 is in the notch 39 and the wheel 20 is adjusted to such a position that the nozzle 18 can engage the floor or carpet, the motion of the casing over the same will result in cleaning the surface both 45 pneumatically and by the brush. In this way both papers and threads can be removed from the surface and the dust also can be drawn up from the bottom of the nap, and in fact even from the underside 50 of the carpet, thus securing a sure, thorough, and effective cleaning action. However, when it is desired to dispense with the use 55 of the brush the only thing necessary is to swing the rod 40 over into the catch 38 and 60 when it is desired to use the brush alone it is simply necessary to have the rod in the notch 39 and adjust the screw 21 until the nozzle is out of effective contact with the surface over which the device moves. It is 65 to be observed that in all three cases the

wheels 11 operate the device in an exceedingly simple manner and that no parts have to be removed and no complicated mechanism has to be adjusted. In addition to this it will be understood that the auxiliary casing with its brush and dust collectors can be removed from the carpet sweeper without affecting the pneumatic action thereof. Moreover, such an auxiliary casing with or without obvious modifications 75 can be applied to any pneumatic cleaner of the proper size and type without modifying it in any way except to saw off a small portion of the casing below the surface 26 or to leave that out in the manufacture of 80 the device. In this way a party having a pneumatic cleaner can add the brush attachment at very small expense, and a party proposing to buy one can get the advantage 85 of the brush sweeper at very low additional cost.

Although I have illustrated and described only a single embodiment of the invention, I am aware of the fact that many modifications can be made therein by any person skilled in the art without departing from the scope of the invention as expressed in the claims. Therefore, I do not wish to be limited to all the details of construction herein shown and described, but

What I do claim is:—

1. In an attachment for the end of a pneumatic carpet cleaner the combination of a casing open at one side and adapted to be attached to the cleaner casing, a shaft therein, 100 a brush on the shaft, power transmitting wheels on the shaft, and two dust pans at the bottom thereof, one extending from the brush to the outer side of the casing, and the other extending from the other side of the brush materially beyond the open side of said casing.

2. An attachment for the end of a carpet cleaner comprising a casing having an opening adapted to communicate with the interior of the cleaner, and having a shaft parallel with said opening, a brush on said shaft, and wheels on said shaft for turning it, said casing having means for collecting the dust from the brush.

3. In a carpet cleaning device, the combination of a main casing, wheels located at one end thereof for supporting it, an auxiliary casing removably attached to the end of said main casing, a brush carried by the auxiliary casing, means connected with the brush for operating it from said wheels, a dust pan pivotally mounted on the auxiliary casing and projecting under said main casing, and means on the pan for operating it.

4. In an attachment for a carpet cleaner, the combination of a casing adapted to be attached to a cleaner casing, a shaft, a brush on the shaft, power transmitting wheels on the shaft, a pair of adjustable brackets on

said casing having bearings for supporting said shaft, and means for moving said brackets into a position to hold the power transmitting wheels in contact with the surfaces of the supporting wheels of the cleaner.

5. In a carpet cleaner, the combination with a casing, of a pair of wheels for assisting in supporting it, a rotary shaft having a brush thereon arranged parallel with the axis of said wheels, a wheel on said shaft adapted to contact with one of said supporting wheels, a pivoted frame on which said shaft is located, means for swinging said frame into a position in which the wheel thereon will be out of contact with the supporting wheel, means at the other end of the casing for supporting that end, and means whereby the last named means can be raised from the surface over which the device travels while the brush remains operative.

6. In a carpet cleaner, the combination with a casing, of a pair of wheels near one end thereof for supporting it, a nozzle at the other end of the casing adapted to support that end of the casing, a brush at the first named end of the casing connected with said wheels for operation thereof, and means for raising the nozzle out of contact with the surface over which the cleaner travels without affecting the operativeness of the brush,

whereby the carpet cleaner can be used as an ordinary sweeper.

7. In a cleaner the combination with a suction producing device; of a suction nozzle; a roller support in driving relation to the suction producing device, said roller support engaging the surface to be cleaned while the nozzle engages said surface; a rotary brush; a roller for rotating the brush; and means for varying the height of the axis of rotation of the brush operating roller and brush with respect to the bottom face of the nozzle.

8. In a cleaner, the combination with a suction producing device; of a suction nozzle for operation upon the surface to be cleaned; a roller support in driving relation to the suction producing device; a rotary brush; a roller for rotating the brush; and means whereby the nozzle is vertically adjustable to change its height with respect to the brush operating roller whereby the cleaner may be constituted either a pneumatic cleaner or merely a sweeper.

In testimony whereof I have hereunto set my hand, in the presence of two subscribing witnesses.

FRANK JULIUS QUIST.
